TURN TABLE DERAILER.

APPLICATION FILED MAR. 11, 1907.

UNITED STATES PATENT OFFICE.

ROBERT OGLE, OF PUEBLO, COLORADO.

TURN-TABLE DERAILER.

No. 884,947.

Specification of Letters Patent.

Patented April 14, 1908.

Application filed March 11, 1907. Serial No. 361,839.

To all whom it may concern:

Be it known that I, ROBERT OGLE, a citizen of the United States, residing at Pueblo, in the county of Pueblo and State of Colorado, have invented certain new and useful Improvements in Turn-Table Derailers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to derailing apparatus for use between railway round-houses and the turntable to which the round - house tracks lead.

It very often happens that the throttle valves of locomotives leak steam whereby the same passes to the cylinder in sufficient quantity to cause the locomotive to run into the turntable pit, assuming that the table is not in line with the track upon which the locomotive is traveling. Accidents of this kind are very serious, since it is a matter of considerable delay and no little expense to remove the engine from the pit. Moreover the locomotive is usually greatly injured.

The object of my present invention, is to make it impossible for the locomotive to reach the pit under the circumstances above named, since it will be derailed or run off the track between the roundhouse and the turntable. This will stop the locomotive, and the latter may be returned to the track at very little expense, as compared with allowing it to run into the pit.

My improved apparatus is automatic in its action and whenever the turntable is not in line with the track, the switch tongue is automatically thrown into position to derail the locomotive, while when the turntable is in line with the track, the switch tongue is held in position to allow the locomotive to keep the straight track and run upon the turntable.

Having briefly outlined my improved construction as well as the function it is intended to perform, I will proceed to describe the same in detail reference being made to the accompanying drawing in which is illustrated an embodiment thereof.

In this drawing, Figure 1 is a top plan view of my improved apparatus, showing a number of tracks leading to the turntable

pit. Fig. 2 is a section taken through the apparatus, the turntable and derailing devices being partly broken away, the parts being shown on a larger scale. Fig. 3 is a top plan view of the turntable showing the buffer plate of the derailing apparatus in section. Fig. 4 is a fragmentary plan view showing a part of the apparatus, the parts being shown on a still larger scale. Fig. 4^a is a similar view showing the portion of the derailing mechanism which is omitted in Fig. 4 for lack of space on the sheet. If Fig. 4^a were placed at the right of Fig. 4 with the two rod members in alinement, the apparatus would be complete. Fig. 5 is a section taken on the line 5—5 Fig. 2 viewed in the direction of the arrow and with the parts on a larger scale. Fig. 6 is a fragmentary view showing the signaling devices connected with the derailing apparatus. Fig. 7 is a section taken on the line 7—7 Fig. 3.

The same reference characters indicate the same parts in all the views.

Let the numeral 5 designate a turntable pit, and 6 the turntable centered therein and adapted to be brought into alinement with sections of track 7 leading to the pit from various directions as from a roundhouse. Connected with one of the rails 7^a of each of these tracks is a switch tongue 8 pivoted at 9, whereby it is permitted to assume either the full line or dotted line position in Fig. 4. When in the full line position it engages an abutment 10 raised along the track and forming a stationary support to maintain the tongue securely in position when arranged to allow the locomotive to take the straight track. This switch tongue is connected with one extremity of a rod 12. The opposite extremity of this rod is pivotally connected with an arm 14 of a bell crank lever 15 fulcrumed at 16. The tongue 8 is also connected by means of a rod 17 with a lever 18 fulcrumed at 19. This arm 18 is provided at its upper extremity with a red glass 20, which when the switch tongue is in position to derail the locomotive, is brought into position in front of a white light lantern 21. This red glass is on the side of the lantern 105 toward the roundhouse so that the danger signal may be seen from the house.

The arm 22 of the bell crank lever 15 is connected at one extremity with a rod 23 which passes between two guide rollers 24 and 25 journaled in angle brackets 26 mounted on a tie 27, the rollers being centrally lo-

cated between the rails of the track 7. The extremity of the rod 23 remote from the bell crank lever is connected with the upturned flange 28 of a plate 29 slidably mounted and retained in position by a guide 30. This plate 29 is provided at its extremity remote from the rod with a depending buffer plate 31 which as shown in the drawing is formed integral with the plate 29. The rod 23 passes through a guide bracket 32 intermediate the slidable plate 29 and the guide rollers 24 and 25. The rod passes through an upturned flange 32^a of this bracket and is slidably freely therein. Between this flange and the flange 28 of the slidable plate 29, is located a coil spring 33, which normally holds the slidable plate 29 together with the curved depending plate 31 in a position corresponding with the dotted line position of the bell crank lever and the switch tongue 8 in Fig. 4. In other words the spring 33 normally holds the apparatus in position to derail a locomotive moving upon the track. When, however, the turntable is in line with the track, a wheel 34 carried by the turntable and horizontally journaled, engages the buffer plate 31, and acts thereon to shift the rod 23 sufficiently to throw the bell crank lever and the switch tongue 8 to the full line position in the drawing. When the switch tongue is in the full line position in the drawing, the lever 18 carrying the red signal 20 is thrown to the position shown in Fig. 6, or out of alinement with the lantern 21. Hence the lantern 35 shows a white light and indicates a clear track. When, however, the switch tongue is shifted to the dotted line position in Fig. 4, the signal lever 18 will be thrown to a position to bring the red signal 20 in alinement with the lantern showing a red light and indicating danger.

The actuating wheel 34 of the turntable, may be mounted thereon in any suitable manner. As shown in the drawing this wheel 34 is journaled in a yoke 35 having a stem 36 passing through ties or cross beams 37 and slidably therein. A spring 38 is interposed between the yoke and the foremost beam 37 and has a tendency to hold the yoke 50 and the wheel in position to be engaged by the buffer plate 31. When it is desired that the wheel 34 shall engage the buffer plate and actuate the derailing apparatus, a stop block 39 is thrown into engagement with the rear 55 extremity of the yoke stem 36 as shown in Figs. 2 and 3. This yoke is connected with a rod 40, the latter being actuated by a lever arm 41 exposed at one side of the turntable. This block 39 forms an abutment against 60 which the yoke stem 36 bears and gives the latter a firm support causing the wheel 34 to act on the buffer plate 31 without yielding. When, however, the block is thrown to the dotted line position in Fig. 7, the wheel and 65 its carriage are free to move rearwardly

against the tension of the spring 38, whereby the wheel 34 has practically no effect upon the derailing apparatus.

It is evident that the invention is not limited to the specific construction disclosed in the drawing. I am aware that many modifications may be employed without departing from the spirit of the invention.

From the foregoing description, the use and operation of my improved device will be readily understood. In Fig. 1, the three tracks 7 on the upper half of the sheet may be considered tracks leading from a roundhouse or connecting the turntable with the roundhouse, while the three lower tracks 70 may be considered ingoing or outgoing tracks whereby locomotives may reach the turntable on their way to the roundhouse, or leave the turntable to go into the yard after 75 leaving the roundhouse.

It will be considered that whenever the turntable is in line with any track 7, the switch tongue 8 is in line to cause the locomotive to keep the straight track to the turntable. When, however, the turntable is out 80 of line with any track 7, the coil spring 33 acting on the slidable plate 39, shifts the rod 23 to open the switch or throw the tongue to the dotted line position in Fig. 4, or in position to derail the locomotive before it runs 85 into the pit.

Having thus described my invention, what I claim is:

1. The combination with a turntable, and a track leading thereto, of a switch tongue, a danger signal connected therewith, mechanism connected with the switch tongue for normally maintaining the latter in the derailing position and the signal in the danger position, the said mechanism having a spring 100 actuated plate part projecting into the path of the turntable, whereby when the latter is in line with the track, it acts on the mechanism to maintain the switch tongue in the non-derailing position, and the signal light in the 105 condition indicating safety or a clear track, substantially as described.

2. The combination with a turntable and a track, of an automatic derailing mechanism comprising the derailer proper, and means for normally holding the derailing device in the derailing position, the said mechanism having a reciprocating plate projecting into the path of the turntable and adapted to be acted on by the latter to maintain 110 the derailer in the non-derailing position, substantially as described.

3. The combination with a turntable and a track leading thereto, of a derailing switch tongue connected with the track, a lever 115 connected with the switch tongue, a spring actuated rod connected with the lever and normally maintaining the switch tongue in the open or derailing position, and a plate 120 connected with the rod and actuated thereby, 125

the said plate projecting into the path of the turntable and adapted to be acted on thereby, to shift the rod and lever into position to maintain the switch tongue in the non-de-
5 railing or clear track position, substantially as described.

4. The combination with a turntable and a track, of a switch tongue, mechanism connected with the switch tongue for normally holding the latter in the derailing position,
10 said mechanism having a buffer plate pro-

jecting into the path of the turntable, whereby the latter acts on the mechanism to maintain the switch tongue in the nonderailing position when the turntable is in line with the track, substantially as described. 15

In testimony whereof I affix my signature in presence of two witnesses.

ROBERT OGLE.
